UNITED STATES PATENT OFFICE.

ABNER DOBLE, OF DETROIT, MICHIGAN, ASSIGNOR, BY MESNE ASSIGNMENTS, TO DOBLE-DETROIT STEAM MOTORS CO., OF DETROIT, MICHIGAN, A CORPORATION OF DELAWARE.

COMBUSTION-HEARTH.

1,313,526.

Specification of Letters Patent.

Patented Aug. 19, 1919.

Application filed January 5, 1917. Serial No. 140,730.

To all whom it may concern:

Be it known that I, ABNER DOBLE, a citizen of the United States of America, and resident of Detroit, Wayne county, Michigan, have invented a certain new and useful improvement in Combustion - Hearths, of which the following is a specification.

My invention relates to improvements in combustion hearths or burner members and 10 more particularly my invention is directed to an improved combustion hearth especially adapted for use in connection with an apparatus for the consumption or combustion of liquid or gaseous fuels.

15 My object is to make an improved combustion hearth of this character which will be simple, durable and reliable in construction, and effective and efficient in operation.

Other objects of my invention will appear 20 hereinafter.

Referring to the accompanying drawings, I illustrate various forms of combustion hearths which embody my invention.

In the drawings:

25 Figure 1 is a view in perspective looking into the interior of my improved combustion hearth or burner member.

Fig. 2 is a vertical section through the structure shown in Fig. 1.

30 Fig. 3 is a section similar to Fig. 2 of a modification.

Fig. 4 is another section similar to Fig. 2 except that the interior thereof is modified.

Fig. 5 is a plan view of still another modified structure.

Fig. 6 is a section substantially on the line 6-6 of Fig. 5.

In the various methods and apparatuses heretofore proposed or used for the combustion of liquid gaseous fuels it has been the practice generally to provide a burner plate or member having a plurality of perforations or openings through which the fuel is passed from one side of the burner to the other in gaseous form, the fuel however having been previously mixed with the proper amount of air to form a combustible mixture, the combustion of the fuel mixture taking place on the side of the plate opposite

50 to that on which the fuel is supplied. This is especially true in the power plants of automobiles of the type where steam is employed as the energizing force and liquid fuel, such as kerosene, used as the source of heat in the generation of the steam. In this

case the liquid fuel is of necessity first vaporized or converted into a gas before being mixed with air and passed through the burner to the combustion side thereof. The necessity of passing the fuel mixture through the combustion member or burner to the combustion side thereof results in inherent objections such as back firing, incomplete and inefficient combustion of fuel, danger of explosion and extreme care necessary on the part of the operator in manipulating the prevaporation mechanism. I burn the fuel mixture in the presence of and in intimate relation to a combustion member which acts catalytically to accelerate and sustain an intense and complete combustion of the fuel, and it is in connection with this combustion member or hearth that my present invention is concerned. In carrying out my system or method heretofore mentioned, of burning fuel I direct the fuel, properly mixed with air, and in either a vaporized or an atomized or finely divided state, upon or against the surface of the combustion hearth in such manner that the combustion of the fuel is concentrated upon or in intimate relation to the hearth surface and in a zone adjacent this surface and the combustion of the fuel in this manner operates to render the combustion hearth, or at least its interior surface, incandescent. The intense zone of heat created by the burning of the fuel, and the incandescent state of said hearth in turn accelerates and sustains the combustion of the incoming fuel. However, in the drawing I have indicated generally a tubular member A by or through which the fuel mixture is introduced to the combustion zone, but this needs no particular description except to say that it is arranged or disposed of in such manner with respect to the hearth that it directs the fuel upon said hearth on the same side thereof on which combustion takes place. This combustion hearth B must be made of highly refractory material which is capable of withstanding intense heat without disintegration, cracking or distortion, and which is capable of becoming incandescent under the influence of this intense heat. This combustion hearth is made generally 105 in the shape of a bowl or dish open at its top, and in the drawings it is shown substantially rectangular, although it may be circular or of any other desirable shape depending upon its particular place of use. It 110

has side walls 10 and a bottom wall 11, the bottom wall being substantially flat and the side wall being disposed generally at right angles thereto, and all of the walls are of 5 practically the same thickness. The thickness of the walls is preferably sufficient to prevent the heat or at least a material degree thereof from penetrating to the exterior of the hearth and for this reason I use 10 a material which is not only highly refractory but also a minimum of heat conductivity. In the several structures shown in the drawings the corners and angles 15 between the side walls and bottom walls are rounded 15 off or curved so as to properly direct the burning gases and keep them circulating in the combustion zone created within the combustion hearth. In the several structures shown in the drawings, the surface area of 20 the interior of the hearth exposed to the burning gases is materially increased by making said surface rough and irregular which has the effect of increasing the area 25 of incandescence of said hearth. Furthermore the forming of the interior in this manner creates innumerable cells or pockets which have the effect of retarding the flow 30 of fuel gases and retaining them for a longer period of time within the combustion zone. 35 The interior of the hearth may be arranged in this manner by forming innumerable projections or irregularities 16 integrally with the hearth itself as indicated in Figs. 1 and 2, or by strewing particles or irregular shaped lumps 17 of refractory material upon 40 the interior surface of the hearth, as indicated in Fig. 3, and securing these in place by welding or otherwise fastening them to the hearth. However, it is not necessary 45 that these particles be secured in place, but in such case it would of course only be possible to retain them upon the bottom wall. I also find it eminently practicable to provide well defined passages or grottoes 18 50 within the combustion chamber by securing in place a number of substantially regular blocks or bricks 19 of refractory material such as indicated in Fig. 4. These are preferably of the same refractory material as 55 the hearth itself and are preferably secured in place by welding or fusing them to each other and to the hearth. Thus the effective incandescent area is increased by the area of 60 these blocks.

55 In manufacturing my improved hearth I preferably mix the refractory material with water or other suitable liquid to make a plastic product and then mold or form this plastic material into the desired shape. The 60 molded form is then baked or heated until the water is completely removed, having a hard, tough structure. I find it desirable to

make the structure extremely porous or absorbent so that in the event that any fuel should reach the hearth, especially in starting the process of combustion in liquid form, it will be instantly soaked up or absorbed by the hearth and then gradually vaporized and released and consumed, the combustion being complete and effectively preventing 70 smoking. A very effective and practicable method of rendering the hearth porous is to mix a quantity of finely divided cork or other combustible material with the refractory material while it is in a plastic condition. Then when the molded form is heated to drive off the moisture the cork or combustible will be consumed and driven off by the heat and leave innumerable pores in the hearth. In Figs. 5 and 6 the fuel mixture is introduced into the combustion chamber in a generally horizontal direction. For this reason the tubular member enters the combustion hearth through a suitable opening in one of the side walls thereof. The fuel is thus directed generally toward the side wall opposite to the fuel tube or nozzle and along and in intimate relation to the interior surface. The burning fuel, however, is deflected by the curvature of the corners and angles and thus circulated within the entire chamber and along the other side walls. In order, however, to prevent the flame from being diverted upwardly I provide an arch 20 which as shown overlies the central portion of the chamber above the stream of fuel emitted from the tubular member. This arch is shown as being formed integrally with the rest of the structure but of course it may be made as a separate piece fitted in place if desired.

I claim:

1. A combustion hearth comprising a member having bottom and side walls and open at its top and composed of porous refractory material and capable of being heated to incandescence, and having its interior roughened or irregular to provide an increased exposed surface area.

2. A combustion hearth of the class described comprising an integral structure of refractory material having bottom and side walls and rounded corners and angles between the side and bottom walls, the interior surface of said structure being roughened and having innumerable projections.

Signed by me at Chicago, Illinois, this 23rd day of Nov., 1916.

ABNER DOBLE.
